UNITED STATES PATENT OFFICE

ARTHUR HENRY BARKER, OF WESTMINSTER, LONDON, ENGLAND

HEATING AND COOLING DEVICE

Application filed January 19, 1929, Serial No. 333,615, and in Great Britain December 30, 1927.

This invention relates to heating and cooling devices for buildings and other structures, the said devices being of the type in which an extended heat radiating plate is maintained at a substantially even and relatively low temperature either by the circulation or flow of hot fluid through passages cast on the back of the plate or otherwise formed in close contact therewith or by the 10 passage of an electrical current through a coil or other electrical heating element situated in such passages or in close contact with the plate.

According to the invention the heating 15 plates are made of suitable length to constitute a single continuous heating unit or are made in sections to constitute single sectional heating units and "dummy" plates or sections are provided for use in connection with 20 the said units which in their external appearance are substantially identical or in keeping with the heating units and have means whereby they can be hinged or otherwise displaceably arranged close to adjacent 25 heating units for covering the space occupied by the valves, taps or switches and the parts associated therewith for controlling the 30 supply of the heating fluid or current so that such parts cannot be seen but are easily accessible for inspection or repair when necessary by displacing the dummy plates. The dummy plates also have holes opposite the actual operating members of the valves, etc., behind the dummy plates to enable said operating 35 members to be reached from the outside without displacing the dummy plates such holes however are so unobtrusive that they are not readily observable and do not therefore materially affect the similitude of the dummy 40 plates with the heating elements which I desire to preserve.

In order that the said invention may be clearly understood and readily carried into effect, the same will now be more fully described with reference to the accompanying drawings, in which:—

Figure 1 is a front elevation of sectional heating units and a dummy plate in the position they occupy when applied as a dado 50 to the wall of the room to be heated.

Figure 2 is a sectional plan taken approximately on the line 2, 2 of Figure 1.

Figure 3 is a vertical sectional elevation taken approximately on the line 3, 3 of Figure 1.

Figures 4 and 5 are similar views to Figure 3 showing modifications.

Figures 6 and 7 are respectively an elevation partly in section and a vertical section taken approximately on the line 7, 7 of Figure 6 of the heating units when arranged vertically on the wall of the room to be heated.

A, A are the heating plates or units having longitudinally and transversely arranged heating passages α , α^1 integrally formed with the back thereof. B is one of the "dummy" plates or sections which are displaceably arranged close to the adjacent heating units for covering the space within which are accommodated the valves C of the hot fluid circulating pipes c , c^1 and the parts with which they are associated, or the switches if the heating is effected electrically. These dummy plates are in keeping with the heating units in appearance except for the holes b which are provided for enabling the stems c^1 of the valves C (or the electrical switches) to be readily reached from the outside without the necessity of displacing the said dummy plates, the said stems c^1 being situated out of view behind the back surface of the dummy plates. In some cases the dummy plates may be made completely detachable and secured in place by means of screws extending through holes registering with corresponding screw-threaded holes in lugs or flanges formed on the adjacent heating units, the said holes in the dummy plates being countersunk to receive correspondingly shaped heads of the screws. The holes in the dummy plates would be preferably elongated to allow of the slight relative movement which takes place during expansion or contraction of the parts. The dummy plates are, however, preferably made displaceable without complete detachment in which case they may be in the form of a hinged door (see Figures 1 and 2) or in the form of a sliding panel. The dummy plates are made

100

somewhat shorter or of less width than the normal space existing between two successive heating units so that when the individual heating units expand under the influence of heat this space is reduced without generating 5 longitudinal stresses.

In Figures 1 to 3 the pipes c, c for the heating fluid are situated outside the skirting board D and reach the uptake pipes c^2 leading 10 to the valves C by branches c^3 extending horizontally through said skirting board. In Figures 4 and 5 the pipes c, c are arranged behind the skirting board so as to be hidden 15 from view, the skirting board being made of metal like the heating units. In Figure 5 the pipes c, c form part of the back or inner surface of the skirting board and in this case only the dado portion of the dummy plate is made detachable.

20 Where the heating units are arranged vertically and the controlling valves, taps or switches and the parts with which they are associated are situated in a space at the bottom as in Figures 6 and 7, the dummy plate 25 is arranged in front of this space and is made in keeping with the skirting board D and the contiguous parts of the heating unit above, said dummy plate being secured in place by screws or made displaceable in the form of a 30 hinged door.

When the heating units are of sectional form as shown the sections are attached together by nipples, bolts or other appropriate means and if the heating is effected by hot 35 fluid the said means of attachment are such as to permit of a continuous flow of the hot fluid in a fluid-tight manner between successive sections and if the heating is effected electrically the means of attachment are such 40 as to permit of the application or insertion in position of the electrically heated coils or elements employed.

The invention has been described in connection with heating but it is suitable also for 45 cooling purposes.

In some cases the dummy plates may be cast from the same pattern as the heating sections but with the heating passages at the back stopped off.

50 By the term "displaceably arranged," I intend to include displacement of the dummy plate with or without its complete detachment.

What I do claim and desire to secure by 55 Letters Patent of the United States is:—

1. A heating device for buildings and other structures, comprising a plurality of heat radiating plates with their adjacent edges in contact and applied to the wall of the room 60 to be heated in the form of a dado, said plates having heating passages arranged at the back thereof, means for supplying and controlling a heating medium to said passages, and dummy plates in keeping with the appearance of 65 said dado displaceably carried by said heat-

ing plates, said dummy plates covering said heat-controlling means and being provided with means for enabling said controlling means to be readily reached.

2. A heating device for buildings and other structures, comprising a plurality of heat radiating plates and dummy plates applied to the wall of the room to be heated in the form of a dado and skirting board, heat supply conduits arranged at the back of said skirting board, and means for supplying and controlling a heating medium from said conduits to said heat radiating plates, said dummy plates covering said heat-controlling means and parts associated therewith and having means for enabling said controlling means to be readily reached. 70 75 80

3. A heating device for buildings and other structures, comprising a plurality of heat radiating plates having heating passages integrally formed with the back thereof, said plates being applied in the form of a dado to the wall of the room to be heated, a skirting board, heat supply conduits arranged at the back of said skirting board, means for supplying and controlling a heating medium from said conduits to the passages of said dado, dummy plates in keeping with the appearance of said dado and skirting board and displaceably arranged adjacent thereto, said dummy plates covering said heat-controlling and supplying means and enabling said means to be inspected or repaired, and operating members forming part of said heat-controlling means and arranged behind said dummy plates, said dummy plates being provided with means for enabling said operating members to be readily reached for actuation through said plates without displacing the latter. 85 90 95 100 105
